(57) **CLAIM**

The ornamental design for a electric cylinder, as shown and described.

DESCRIPTION

FIG. 1 is a front view of a electric cylinder of the present invention.

FIG. 2 is a rear view of the electric cylinder of FIG. 1.

FIG. 3 is a top plan view of the electric cylinder of FIG. 1.

FIG. 4 is a bottom view of the electric cylinder of FIG. 1.

FIG. 5 is a right side view of the electric cylinder of FIG. 1.

FIG. 6 is a left side view of the electric cylinder of FIG. 1.

FIG. 7 is a reference perspective view of the electric cylinder of FIG. 1.

FIG. 8 is a front view of another electric cylinder of the present invention.

FIG. 9 is a rear view of the electric cylinder of FIG. 8.

FIG. 10 is a top plan view of the electric cylinder of FIG. 8.

FIG. 11 is a bottom view of the electric cylinder of FIG. 8.

FIG. 12 is a right side view of the electric cylinder of FIG. 8.

FIG. 13 is a left side view of the electric cylinder of FIG. 8;

and,

FIG. 14 is a reference perspective view of the electric cylinder of FIG. 8.
